Primary Examiner — Shannon W Morgan*Assistant Examiner* — Rodolfo Castro, Jr.(74) *Attorney, Agent, or Firm* — Philip Oweimrin(57) **CLAIM**

The ornamental design for a mobile phone accessory, as shown and described.

DESCRIPTION

FIG. 1 is a front perspective view of a mobile phone accessory, showing my new design;

FIG. 2 is a rear perspective view thereof;

FIG. 3 is a side perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof;

FIG. 10 is a perspective view showing the mobile phone accessory in a use state; and,

FIG. 11 is an enlarged detail view of area 11 in FIG. 2.

The broken lines shown in FIG. 10 depict environmental subject matter and form no part of the claimed design. The dash-dot-dash broken lines encircling the enlarged views are for annotative purposes only and form no part of the claimed design.

1 Claim, 11 Drawing Sheets(56)
